(57) **CLAIM**

The ornamental design for an impedance meter, as shown and described.

DESCRIPTION

FIG. 1 is a front, right side, bottom perspective view of an impedance meter showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view thereof showing a state in which the impedance meter is attached to a body composition meter; and,

FIG. 9 is a reference view thereof showing a state in which this article is used.

The portions in broken lines are shown for illustrative purposes only and form no part of the claimed design.
